DESIGN FOR A SERVING DISH OR SIMILAR ARTICLE

Joseph Davis, South Orange, N. J., assignor to Joseph Davis Plastics Co., Arlington, N. J., a corporation of New Jersey

Application January 9, 1946, Serial No. 125,372

Term of patent 14 years

(Cl. D44—15)

To all whom it may concern:

Be it known that I, Joseph Davis, a citizen of the United States, residing in South Orange, county of Essex and State of New Jersey, have invented a new, original, and ornamental Design for a Serving Dish or Similar Article, of which the following is a specification, reference being had to the accompanying drawing, forming a part thereof.

Fig. 1 is a top plan view of a serving dish or similar article embodying my new design,

Fig. 2 is a side elevational view thereof taken on line 2—2 of Fig. 1, and

Fig. 3 is a side elevational view thereof taken on line 3—3 of Fig. 1.

The dominant features of my design reside in the portions shown in full lines.

I claim:

The ornamental design for a serving dish or similar article, as shown and described.

JOSEPH DAVIS.

Certificate of Correction
